UNITED STATES PATENT OFFICE.

LAWRENCE B. KOHNLE AND WILLIAM B. HAMILTON, OF LIMA, OHIO, ASSIGNEES TO JAMES IRVINE, OF SAME PLACE.

DROP-LIFT STEP FOR MILL MACHINERY.

SPECIFICATION forming part of Letters Patent No. 276,603, dated May 1, 1883.

Application filed March 1, 1883. (No model.)

To all whom it may concern:

Be it known that we, LAWRENCE B. KOHNLE and WILLIAM B. HAMILTON, both citizens of the United States, residing at the city of Lima, in the county of Allen and State of Ohio, have jointly invented certain new and useful Improvements in Drop - Lift Steps for Mill Machinery; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to drop - lift steps for mill machinery.

Our invention relates to that class of drop-lift steps which are applied to upright shafts having gear-wheels thereon, for the purpose of throwing said gear-wheels into engagement with others on the ends of horizontal shafts by elevating the shaft by means of the step. It is mainly used to engage the driving-gear with that on shafts in reel-chests, purifiers, &c. In the present state of the art the engaging gear is bevel, although other kinds might be used.

Our invention pertains only to the step which forms the end bearing and support for the upright gear-bearing shaft.

The object of our invention is to produce a drop-lift step which is simple in construction, which cannot get out of order, is easily operated, and which is adapted to all kinds of upright gear bearing shafts which are required to be elevated; also which is provided with an anti - frictional and reversible bearing for the shaft. It consists of a step in two sections, one of which slides into the other, the inner section provided with a socket or oil-pot, in the bottom of which is a reversible anti-frictional button forming the end bearing for the shaft, which is elevated by a direct lift. The construction of the step is such as to allow of its being operated in any position where placed, thereby dispensing with the necessity of the double cost of a right and left step, such as are ordinarily in use. Unlike this latter form of construction, which operate to elevate the shaft by a partial rotation of the male section, our

step is operated by a cam which operates against the lower end of said male section directly in the axial line of the shaft. The support is also central with this line, thereby preventing that liability to wear on one side more than another which is often found in steps having peripheral bearings.

Figure 1 is a top view of our improved drop-lift step. Fig. 2 is a side elevation of the same. Fig. 3 is a vertical section through line 1 2, 6. Fig. 1. Fig. 4 is a cross - section through the base, and a view of the lower end of the male section shown inserted therein. Fig. 5 is a top view of the cam which operates against the lower end of the male section to elevate the 65 shaft. Fig. 6 is a view of the cam shaft or pin.

The step consists of the two sections A and B. The former, being the male section, slides into the latter, which forms the fixed base of the step. As will be seen in Fig. 4, both are cylindrical in their cross-section. The male section A is cast with a cavity which forms the cup or socket for the end of the upright shaft *a*, and is usually called the "oil-pot." Central in the bottom of this cavity is a raised boss, *b*, and on this is a lens-shaped button, *c*. It is oblong in shape and convex on both sides, to make it reversible, so that when worn on one side it may be turned over, and also to make it as nearly anti-frictional as possible. Its ends extend nearly to the walls of the cavity, and are held down by the bush-ring *d*, which fits down snugly into the socket *a'*, and is secured by a split pin, *e*, which enters oppositely-registering grooves in the ring and in the wall of the socket. 85 The pin *e* has a flanged head, like a rail-spike, to allow it to be withdrawn when necessary.

By reference to Fig. 3, it will be seen that there is ample room around the button and lower end of the shaft to allow the latter to 90 run for some time without its gumming or requiring renewal of the oil-supply. Oil-holes *i* (seen in the plan view, Fig. 1) are provided for this purpose. These lead down from the top of the oil-pot, on either side, into the cavity or reservoir *c'* at the bottom of the socket *a'*. As the edges of the button on its longest sides do not extend out to the ring *d*, the passage of the oil to the reservoir *c'* is not obstructed, and the oil, when even as low as the 100

top of the button, is drawn in under the end of the shaft as it rotates, keeping it thoroughly lubricated. On one side of the male section or oil-pot A, near its lower end, is seen a short 5 rib or feather, b', extending therefrom, which engages with a vertical groove, d', in the inner wall of the base on one side, (at right angles with the shaft f of the cam c.) The object of this rib and groove is to prevent any shifting of the male section axially when lifted, as well as to avoid all possibility of the gear being jarred out of engagement. The lower end 10 of section A is formed not only for the operative movement of the cam c, but also to allow it to rest upon the base when let down, and thereby relieve the cam from the superincumbent weight and allow it to be brought more readily into operation. The incline i' on the end of A, when the latter is at its lowest point, rests 15 upon the incline i'', which projects inward from the inner wall of B, as seen on the right in Fig. 3. The dotted lines in this figure show the position of section A when down, and of the cam c before being operated to elevate it. 20 The cam is pear-shaped in cross-section, being extended upon one side a little more than one-half its diameter to give it sufficient throw to elevate the male section A the desired height necessary to engage the gear. The extended 25 side of the cam c' has a square plane surface, which, when the cam is turned upward to the position seen in Fig. 3, allows the horizontal plane surface d'' on the lower end of A to rest thereon, giving it a firm seat and locking the cam in position. It will be noticed that the 30 axial line of the shaft a will cut the cam-shaft f through the center. A square recess, h, allows the insertion of the cam into its position in the base B before the latter is bolted down 35 to its place, and the shaft f is inserted through a diametric hole in the base and through the interposed cam. To retain the shaft in its position in the cam and prevent the latter from turning thereon, as well as to provide for the 40 partial revolution of the shaft in its bearings in the walls of the base, it is planed off longitudinally from its inserted end to a point reaching to within a short distance of the head, so as to form an angle extending throughout 45 that portion of its length. The hole in the cam is made of the same (reversed) form. Upon the end g is formed a square head to the cam-shaft to provide for its being operated by a common nut-wrench lever. 50

55 By reference to the view Fig. 3 the construction of the operative parts of our improved step can be plainly seen. The dotted lines show the movement of the movable section and its position, both at the lowest and highest 55 point. The position of the cam c when in its normal position is also seen. The upper dotted line shows that the oil-pot or bowl section A is lifted a little higher than the position in which it is seen seated or locked by the operation of 60 the cam, the angle n of which, being farther from the center of the pivotal shaft f, necessa-

rily elevates it to the height of the line x as the cam is turned over, and it then falls back to its seat upon the plane side e'' of the cam. The under surface of A on the left (in Fig. 3) is 70 curved to allow the cam to be more easily operated in lifting the gear-bearing shaft. It will be noticed that the seat of the movable section A upon the plane flat surface of the cam is directly in the line of the shaft a, locking it firmly, 75 so that it is in no degree liable to be displaced, nor is it subject to wear. In case of uneven wear the bush-ring may be reversed.

The operation of the device is so simple as to be readily understood by reference to the drawings, which sufficiently illustrate the movement of the operative parts.

We claim as our invention—

1. In a drop-lift step, a cam located beneath the movable section, upon a shaft pivoted in 85 the walls of the base and adapted to operate said section, to lift it by a partial rotation of said cam, substantially as set forth.

2. In a drop-lift step, a cam for operating the same, pivoted under the movable section, and 90 having one side of its face formed into a seat for the end of said movable section to rest upon when elevated, said cam being fixed upon a shaft or pin pivoted at right angles to the vertical walls of the step, and adapted to elevate 95 the gear-bearing shaft by a partial rotation of the same, and to retain said gear-bearing shaft in position, when elevated, by the pressure of the movable section of the step upon said cam-seat, substantially as shown and specified. 100

3. A cam for operating the movable section of a drop-lift step, having a flat seat upon one side of its face, with an angle projecting beyond the circle of rotation of said seat, whereby said movable section (with its gear-bearing shaft) is elevated above it when the cam is operated, and allowed to fall back and become locked in position, as hereinbefore specified. 105

4. In a drop-lift step having a fixed and a 110 movable section, a rib upon one section engaging with a groove in the other section, as and for the purpose hereinbefore set forth.

5. A drop-lift step having an operative cam for lifting its movable section, a shaft pivoting said cam in the walls of the base, said shaft being formed with one or more angles extending from its insertible end longitudinally toward the head, and adapted for insertion through a hole of like reverse shape in the 120 cam, as and for the purpose set forth.

6. In a drop-lift step for mill machinery, an anti-frictional reversible button having both its sides convexed, and adapted to operate as a seat for the gear-bearing shaft, as set forth. 125

7. A button for drop-lift steps, of oblong form, its ends extending under the bush-ring and supporting the same, and having its two sides made convex, whereby it is made reversible, as set forth.

8. In a drop-lift step having its movable section cast or bored with a cavity or socket for

the end of the gear-bearing shaft, and having a button seated therein, upon which said shaft is stepped, the combination of a raised boss, central with said cavity, in the bottom thereof, to form a seat for said button, substantially as set forth.

9. A drop-lift step bearing within its base a projection or other equivalent means for forming a rest for the end of the movable section, to relieve the cam from the superincumbent weight of the gear-bearing shaft, and to allow it to be more readily brought into operation.

10. In a drop-lift step having an insertible bush-ring grooved on one side to form a hole, with an opposite groove in the inner wall of its bowl or socket, the combination therewith of a split pin having a flanged head, whereby said ring may be removed by the withdrawal of said pin, as set forth.

11. In a drop-lift step having a fixed and a

movable section telescoped together, and operated by a vertical movement, as set forth, the combination, with said sections, of a rib upon one section engaging with a groove in the other, as and for the purpose specified. 25

12. In combination with the movable section and the fixed base, the operative cam and the pivoted shaft, the latter extending diametrically through the base, across the axial line of the gear-bearing shaft supporting said cam, 20 upon the middle thereof, and adapted to operate substantially as set forth.

In testimony whereof we affix our signatures in presence of two witnesses.
